UNITED STATES PATENT OFFICE

2,601,970

HOIST

Harold F. Minnis, Claremont, N. H., assignor to
Joy Manufacturing Company, Pittsburgh, Pa.,
a corporation of Pennsylvania

Application July 25, 1949, Serial No. 106,696

7 Claims. (Cl. 254—185)

1

This invention relates to a hoist, especially to a hoist of the type used in the operation of slushers, or mucking scrapers, as they are sometimes known.

In the operation of slusher hoists, it is customary to use two cable drums which are mounted to be freely rotatable on a continuously rotating shaft. A clutch connects the shaft with a selected drum, the selection depending upon the direction in which the operator chooses to move the slusher. Under the conditions of use in many slusher installations, the clutches are likely to become very hot and may thereby cause overheating of the metal clutching surface.

It is accordingly an object of this invention to provide a slusher hoist in which the clutching surface may be operated with a minimum of down time of the machinery and with a minimum danger of damage due to overheating. It is another object of this invention to provide a slusher hoist with a maximum effectiveness of control.

The foregoing and other objects are accomplished in a slusher hoist in which a disc type of clutch is engaged by frictional elements which are hydraulically controlled.

In the drawings:

Fig. 1 is a side elevation of a slusher hoist embodying the invention.

Fig. 2 is a view in elevation from the right end of the machine shown in Fig. 1.

Fig. 3 is a partial view in section, substantially on line 3—3 of Fig. 2 with parts omitted.

Fig. 4 is a longitudinal sectional view through the hoist shown in Fig. 1.

Fig. 5 is a schematic view showing the hydraulic circuit of the hoist control means.

Fig. 6 is a view similar to Fig. 2, but showing a modification of the invention, and

Fig. 7 is a schematic view showing the hydraulic circuit of a hoist control made according to the modification shown in Fig. 6.

The hoist shown discloses a conventional skid type support or base 2 on which are mounted the two rotating drums, later described, and the drive motor 4. The drive motor 4 is shown as being mounted directly on the housing 6 of the gear reduction unit 8. A hydraulic fluid pump 10 is mounted in the housing 6 and is connected to be driven by the motor 4, and supplies fluid under pressure for control of the system through a conduit 12.

The gear reduction unit 8 comprises a drive pinion 14 mounted on the motor shaft 16. A

5 relatively large gear 18 meshes with pinion 14 and is supported on a countershaft 20 which is rotatably mounted in suitable bearings. A second pinion 22 is mounted for rotation by and with gear 18 by means of integral connecting hollow shaft 24. A second comparatively large gear 26 meshes with gear 22 and is mounted on a drive shaft 28. Drive shaft 28 is rotatably supported in antifriction bearings 30 and 32 in 10 the housing 6 and in end pedestal or support 34, respectively.

Cable drums 36 and 38 are mounted side by side for rotation on shaft 28 by means of suitable antifriction bearings 40. The drums 36 and 38 are freely rotatable with respect to shaft 28. As is best seen in Fig. 4, drum 36 is nearer the motor 4 than is drum 38.

Drums 36 and 38 are provided with cylindrical brake surfaces 42, and conventional brake bands 20 44 are mounted in position to have frictional engagement with the surfaces 42. The controls for the brake bands 42 may be conventional and need not be detailed herein.

A sun gear 46 is keyed to shaft 28 and is therefore driven thereby. Sun gear 46 is mounted between the motor 4 and the nearer cable drum 36; more specifically gear 46 is mounted between the gear reduction unit 8 and the drum 36. On the other side of the two cable drums 36 and 38 from the motor, there is mounted another sun gear 48. Sun gear 48 is likewise keyed to shaft 28 and is driven thereby. A planet carrier 50 is shown as being integral with drum 36 and consists of a tubular member 52 and a planet gear shaft 54 carried in the tubular member 52. Similarly a planet carrier 56 is integral with drum 38 and consists of a tubular member 58 and a planet gear shaft 60.

A planet gear 62 is mounted for rotation on 40 suitable antifriction bearings on one end of shaft 54 and meshes with sun gear 46. Although more than one planet gear 62 may be used as will be understood by those skilled in the art, only one is shown in Fig. 4. A planet gear 64 45 is mounted on one end of shaft 60 on suitable antifriction bearings and meshes with sun gear 48.

An end member 66 is mounted for rotation on shaft 28 by means of suitable bearings and is disposed between the motor 4 and the sun gear 46, immediately adjacent the latter. A second end member 68 is mounted for rotation on shaft 28 on suitable antifriction bearings and is disposed immediately adjacent sun gear 48 at the end of shaft 28 opposite motor 4.

An internal gear 70 is secured to end member 66 for rotation therewith by means of a number of threaded members, one of which is shown at 72. Gear 70 is mounted to mesh with planet gear 62. Similarly an internal gear 74 is secured to end member 68 for rotation therewith by means of threaded members, one of which is shown at 76.

A disc clutch 78 is mounted integral with end member 66 and extends radially outward therefrom. Another disc clutch 80 is preferably integral with end member 68 and extends radially outward therefrom.

As is best seen in Figs. 3 and 5, hydraulically actuated friction means are positioned to be engageable with the disc clutches. Only one end member, namely 68, and its associated disc clutch and friction means can be seen in Fig. 3, but the other friction means are substantially the same, so the showing in Fig. 3 will suffice. As can be seen in that figure, a pair of hydraulic cylinders 82 and 84 are disposed in aligned relation at opposite sides of the disc 80. Reciprocally disposed in cylinders 82 and 84 are pistons 86 and 88, respectively. Pistons 86 and 88 bear against the stems of clutch pad carriers 90. The faces of the clutch pad carriers 90 are provided with any suitable friction material or clutch facing 92.

It will be understood by those skilled in the art that additional pairs of opposed clutching cylinders may be provided if desired, as for example those shown at 94 and 96.

It will further be understood by those skilled in the art that similar hydraulic operating cylinders may be provided for the disc 78, as shown schematically in Fig. 5. The hydraulic clutching cylinders there shown in position to engage disc 78 may be identified by the reference characters 98, 100, 102 and 104.

The hydraulic system to operate and control the clutches will now be set forth in further detail. As was described above, a fluid pump 10 is connected to be driven by motor 4. Pump 10 draws hydraulic fluid from a sump or tank 106 by way of a conduit 108. The pump discharges fluid under pressure into conduit 12 to a control valve 110. Control valve 110 consists of an entrance or high pressure section 112, an exhaust section 114 and control sections 116 and 118. Suitable handles 120 and 122 are provided to enable control of the fluid supply to the various clutch operating cylinders and the venting of fluid therefrom. Except when the handles 120 and 122 are manipulated to effect fluid supply to the clutch operating cylinders, these are vented to the sump or tank 106.

As is evident from Fig. 5, conduit 12 discharges into the high pressure section 112 and a drain or exhaust conduit 124 connects the exhaust section 114 with the tank 106. A conduit 126 connects control section 116 of the valve with the hydraulic clutching cylinders for disc 78 by way of branches 128, 130, 132 and 134. A conduit 136 connects control section 118 with the clutching cylinders for disc 80 by way of branches 138, 140, 142 and 144.

Referring now to the embodiment of the invention shown in Figs. 6 and 7, these figures show a hoist made according to the invention, but in which a pair of hand operated pumps takes the place of the motor operated pump 10 of the embodiment shown in Figs. 1-5. The manually operated levers 150 and 152 are directly connected to the pistons 154 and 156 of pump cylinders 158 and 160 respectively. Conduit 162, with its

branch conduits 164, 166, 168 and 170 connects the cylinder 158 with the clutch cylinders 172, 174, 176 and 178 of the clutch disc 78'. A conduit 180, with its branches 182, 184, 186 and 188, connects the cylinder 160 with the clutch cylinders 190, 192, 194 and 196 of clutch disc 80'.

As will be understood by those skilled in the art, the pump cylinders 158 and 160 may be any of a number of suitable types. The details shown in Fig. 7 are intended to be merely schematic to illustrate the principle. Cylinders 158 and 160 will preferably be supplied from any suitable reservoir 198 through conduits 200 and 202 provided with check valves 204 and 206. The two reservoirs 198 may be a common reservoir for both pump cylinders.

Operation

As will be understood by those skilled in the art, a slusher hoist of the type described is operated by driving one cable drum or the other, according to the direction in which the operator desires to move the drag bucket or slusher.

As the operating handle 122 is manipulated to admit fluid under pressure to the conduit 136, the fluid in the branch conduits 138, 140, 142 and 144 is simultaneously subjected to pump discharge pressure (except for losses through the lines). The cylinders 82, 84, 94 and 96 are thereupon subjected to fluid under pressure, and their respective pistons are moved toward the disc 80, bringing the friction material of the clutch pads into engagement with the disc. As the clutch disc 80 is slowed down, the planet gear 64 begins to rotate in its orbital path about the shaft 28, carrying with it its shaft 60, tubular member 58 and thereby the drum 38. A maximum drive speed of drum 38 will be attained when clutch disc 80 is brought to a complete stop.

The drive of drum 38 is similarly accomplished and need not be detailed here.

The two clutch discs 78 and 80 extend radially outward from their supports into the surrounding atmosphere and may be cooled by conduction and radiation to the surroundings.

From the foregoing description of the operation of the embodiment shown in Figs. 1-5, it will be evident to one skilled in the art how the embodiment of Figs. 6 and 7 operates. It need only be noted here that manipulation of levers 150 and 152 itself provides the fluid pressure for the actuation of clutches 78' and 80' through the medium of pump cylinders 158 and 160.

It will be evident to those skilled in the art that this invention provides a slusher hoist having an improved drive and control means therefor.

While there are in this application specifically described two forms which the invention may assume in practice, it will be understood that these forms of the same are shown for purposes of illustration, and that the invention may be modified and embodied in various other forms without departing from its spirit or the scope of the appended claims.

I claim:

1. In a slusher hoist, a shaft; means to drive the shaft; a cable drum freely rotatable on the shaft; a planetary gear train associated with the drum and having sun and planet gears in mesh, a planet carrier comprising a tubular member integral with the drum and a planet gear supporting shaft carried in the tubular member, and an internal gear, the planet and internal gears being also in mesh; a clutch having cooling

means including a radially outward extending disc secured to the internal gear and being freely rotatable on the shaft; friction means associated with the disc and movable to engage both sides of the disc; hydraulic cylinder-and-piston means connected to operate the friction means; and valve means to control the last named means.

2. A hoist according to claim 1, in which the friction means and hydraulic cylinder-and-piston means comprise a pair of aligned cylinders disposed on opposite sides of the clutch disc, a piston movable in each such cylinder, and a clutch pad connected to the piston for movement therewith.

3. In a slusher hoist, an electric motor, a shaft rotatably mounted in bearings, a gear train connecting the motor with the shaft, a cable drum rotatably mounted on the shaft, a sun gear mounted on the shaft for rotation therewith and thereby, a planet carrier shaft mounted in the drum, a planet gear on the planet carrier shaft and meshing with the sun gear, a rotatable end member mounted on the shaft adjacent the sun gear, an internal gear secured to the end member and meshing with the planet gear, an air-cooled disc clutch integral with the end member and projecting radially outward therefrom, a pair of opposed cylinders on opposite sides of the disc, pistons reciprocably mounted in the cylinders, clutch pads on the pistons and positioned adjacent the clutch disc, hydraulic fluid connections to the cylinders, a source of fluid under pressure and means to control the admission of fluid to the cylinders.

4. In a slusher hoist, a shaft; means to drive the shaft, two cable drums freely rotatable on the shaft; a planetary gear train associated with each drum and having sun and planet gears in mesh, a planet carrier, and an internal gear, the planet and internal gears being also in mesh and the planet carrier being integral with the drum; a clutch having cooling means including a radially outward extending disc secured to each internal gear and freely rotatable on the shaft; friction means associated with each disc and movable to engage both sides of the disc; hydraulic cylinder-and-piston means connected to operate the friction means; and valve means to control the last named means.

5. A hoist according to claim 4, in which the friction means and hydraulic cylinder-and-piston means comprises a pair of aligned cylinders disposed on opposite sides of the clutch disc, a piston movable in each such cylinder, and a clutch pad connected to the piston for movement therewith.

6. In a slusher hoist, an electric motor, a shaft rotatably mounted in bearings, a gear train connecting the motor with the shaft, a pair of cable drums rotatably mounted side-by-side on the shaft, a pair of sun gears mounted on the shaft

for rotation therewith and thereby, there being one sun gear between the electric motor and the nearer of the two drums and another on the far side of the drums from the motor, a planet carrier shaft mounted in each drum, a planet gear on each such planet carrier shaft and meshing with its cooperating sun gear, a rotatable end member mounted on the shaft for each sun gear, there being one such end member between the motor and the nearer sun gear and another on the far side of the other sun gear from the motor, an internal gear secured to each end member and meshing with a planet gear, an air-cooled disc clutch integral with each end member and projecting radially outward therefrom, a pair of opposed cylinders on opposite sides of each disc, pistons reciprocably mounted in the cylinders, clutch pads on the pistons and positioned adjacent a clutch disc, hydraulic fluid connections to the cylinders, a source of fluid under pressure, and means to control the admission of fluid to the cylinders.

7. In a slusher hoist, an electric motor, a shaft rotatably mounted in bearings, a gear train connecting the motor with the shaft, a cable drum rotatably mounted on the shaft, a sun gear mounted on the shaft for rotation therewith and thereby, a planet carrier shaft mounted in the drum, a planet gear on the planet carrier shaft and meshing with the sun gear, a rotatable end member mounted on the shaft adjacent the sun gear, an internal gear secured to the end member and meshing with the planet gear, an air-cooled disc clutch integral with the end member and projecting radially outward therefrom, a pair of opposed cylinders on opposite sides of the disc, pistons reciprocably mounted in the cylinders, clutch pads on the pistons and positioned adjacent the clutch disc, hydraulic fluid connections to the opposed cylinders, and a manually operable pump connected to the hydraulic fluid connections.

HAROLD F. MINNIS.
